UNITED STATES PATENT OFFICE.

EDOUARD HENRI FRÉDÉRIC DE TURCKHEIM, OF PARIS, FRANCE.

DESIGN FOR A BONNET FOR AUTOMOBILE VEHICLES.

46,484.

Specification for Design.

Patented Sept. 29, 1914.

Application filed May 26, 1913. Serial No. 770,083. Term of patent 7 years.

To all whom it may concern:

Be it known that I, EDOUARD HENRI FRÉDÉRIC DE TURCKHEIM, a citizen of the French Republic, residing at 4 Rue de l'Arcade, Paris, France, have invented a new and original Design for Bonnets for Automobile Vehicles, of which the following is a specification, reference being had to the accompanying drawing, forming part thereof.

Figure 1 is a perspective view of the bonnet showing a new design, Fig. 2 is a front view of the bonnet, and Fig. 3 is a side view of the front portion of the bonnet.

The bonnet consists essentially of an upper curved surface A, of two lateral vertical faces B each joined to the surface A by an inclined plane C, and a forward face D open to receive the radiator. The upper surface A comprises a main curved convex part prolonged on each side by a concave part, which adjoins the inclined plane C.

The forward vertical surface D is rounded at the upper part D¹ in such manner as to join tangentially to the surface A, as is clearly seen from the Fig. 3. The edges of the inclined planes C are preferably slightly rounded.

The length and the width of the bonnet, the width of the inclined planes at the height of the vertical faces are variable. The same is true of the radii of curvature, whether of the upper surface or of the rounded portion of the forward face.

I claim—

The ornamental design for a bonnet for automobile vehicles, substantially as shown and described.

EDOUARD HENRI FRÉDÉRIC DE TURCKHEIM.
